UNITED STATES PATENT OFFICE.

ERNEST LEWIS, OF BURLINGTON, NEW JERSEY.

CUT-OFF REGULATOR AND INDICATOR FOR STEAM-ENGINES.

1,246,621.

Specification of Letters Patent. Patented Nov. 13, 1917.

Application filed October 24, 1916. Serial No. 127,417.

To all whom it may concern:

Be it known that I, ERNEST LEWIS, a citizen of the United States, and a resident of Burlington, county of Burlington, State of New Jersey, have invented Cut-Off Regulators and Indicators for Steam-Engines, of which the following is a specification.

My invention relates to a device for accurately indicating the range of cut off in the various cylinders of a compound engine and for adjusting the ranges relative to one another so as to obtain those which are most efficient and economical. The manifold advantages of such a device, whereby instantaneous adjustments may be made to meet the variant conditions occurring in the operation of these engines, will be apparent to one skilled in the art.

The device herein described has a special application to engines having the Corliss valve gear and consists in a novel arrangement of the reach rods controlling the cut off mechanisms, wherein a link is interposed between the rods of the high and low pressure cylinders. The link carries a set screw which when turned varies the range of cut off in the low pressure cylinder, there being a corresponding variation in the range of the high pressure cut off due to the action of the governor, to which the reach rods on the high pressure side are connected. To points on the link, or allied members, are attached by suitable connecting means the pointers of a compound indicating gage which is set to indicate the exact range of cut off in the cylinders.

Referring to the drawings:

Figure 1 is a view in side elevation of a tandem engine having the Corliss valve mechanism, showing the distribution of the reach rods, link and gages.

Figs. 2 and 3 are views showing the details of the link.

Figs. 4 and 5 are views showing the details of the gage.

Figs. 6 and 7 are views in perspective of the pointers of the gage.

In Fig. 1, 1 is the governor which is connected through a bell crank 2 and a rod 3 to a link arm 4 pivotally mounted on an arm 5 held by the bracket 6, attached to any suitable point on the engine body, in the present case to the low pressure cylinder casing. To the link arm 4 are attached reach rods 7 and 8 which connect at their other extremities with the levers 9 and 10

respectively on collars bearing cams 11 and 12 which trip the cut off mechanism of the high pressure cylinder 13 at the desired point in the stroke. The governor acts directly upon the high pressure cut off mechanism through the various rods and the link.

Pivoted on the arm 5 and capable of independent movement relative to the link arm 4 is an arm 14 which is adjustably connected at its outer end to the arm 4 by means of an adjusting screw 15, said adjusting screw entering threaded bearings 16 and 17 in the extremities of the two arms. Attached to the arm 14 at a suitable point is a rod 18 which is attached to a lever 19 on a collar bearing a cam 20 which trips the cut off mechanism at one end of the low pressure cylinder 21. Upon the cam collar which bears the lever 19 is a lever 22 which is connected through the reach rod 23 with a lever 24 on a collar bearing a cam 25 which trips the cut off mechanism at the other end of the low pressure cylinder. It will be seen that the mechanism controlling the ranges of cut off in the cylinders are adjustably connected to one another through the various rods, the link arms 4 and 14 and the screw 15.

Attached at suitable points to the link arms 4 and 14 are rods 26 and 27, which form connections with the indicating means. The indicator is shown in detail in Figs. 4 and 5. Within the casing 28 are pivotally mounted the segmental gears 29 and 30 each

having an extension, respectively 31 and 32, to the extremities of which are connected the rods 26 and 27. These gears mesh with the segmental gears 33 and 34 which are pivotally mounted as shown and which carry

the hands or pointers 35 and 36, said pointers indicating respectively the range of cut off in the high and low pressure cylinders. It will be noticed that a single graduated scale, 37,

is used for both the high and low pressure pointers, this being made possible by the bending over and downward of the rear pointer, as clearly shown in Fig. 6. The rods 26 and 27 are furnished with adjusting

screws 29 and 40 so that the proper positions for the pointers may be easily obtained on installation. There must be room in the gage to accommodate the movement of the hands when the governor drops to the low position. At 41, Fig. 1, is shown a recording

gage of the same general construction, by means of which the range of cut off in the

high pressure cylinder may be recorded during the period of operation of the engine.

The following is one method for calibrating the scale of the gage. The travel of the high pressure piston may be laid off on the crosshead guide as defined by the position of the crosshead when the engine is on its dead centers, and this distance divided into any number, say ten, of equal parts. The engine is then turned over in the direction it is to run until the edge of the crosshead coincides with the second division on the guide. With the valve gear hooked up, the governor is raised by means of a fine threaded screw until the valve is tripped. This position represents a cut off at one tenth of the stroke and the high pressure pointer should indicate such on the gage scale. This procedure is repeated for the other points. For the low pressure cylinder the procedure is the same with the exception that the adjusting screw 15 is used to trip the valve mechanism.

The operation of the device as herein described will be apparent to those acquainted with the art. The operator, on turning the adjusting screw 15, will notice a change in the range of the low pressure cut off as shown on the gage, and a corresponding change in the range of the high pressure cut off due to the action of the governor will follow. By turning the screw he will be able to so adjust the cut off in the low pressure cylinder as to obtain the earliest possible cut off in the high pressure cylinder. The adjustment is instantaneous and a great saving of steam is made possible.

It will be understood that though I have described my invention in relation to but one type of compound engine, I do not wish to limit myself to a single application, as the device is capable of application to all forms of compound engine embodying the Corliss or puppet valve mechanisms.

45 I claim:

1. In a compound engine, the combination with high and low pressure cylinders,

of inlet and outlet valves therefor, a governor, means connecting the governor with the inlet valves of the high pressure cylinder, manually adjustable connecting means between the aforesaid connecting means and the inlet valves of the low pressure cylinder, whereby the cut off of the low pressure valves may be independently adjusted, and means connected to said connecting means for indicating the range of cut off in the cylinders.

2. In a compound engine the combination with high and low pressure cylinders, of inlet and outlet valves therefor, a governor, a link mechanism consisting of two pivoted arms, the governor and high pressure valve mechanism being connected to one arm and said low pressure valve mechanism being connected to the other arm, and a manually operated adjusting member connecting said pivoted arms for independently adjusting the cut off in the low pressure cylinder.

3. In a compound engine, in combination with high and low pressure cylinders supplied with cut off valves, a governor, a link mechanism comprising two pivoted lever arms, rods connecting one arm to the governor and to the cut off valves of the high pressure cylinder, rods connecting the other arm to the cut off valves of the low pressure cylinder, and an adjusting member connecting the two arms whereby an independent adjustment of the low pressure cut off may be obtained.

4. In combination with the governor and valve mechanism of a compound engine, a link consisting of two arms pivotally mounted and adjustably connected, a rod connecting one arm to the governor, said arm being also connected to the cut off mechanism of the high pressure cylinder and said other arm being connected to the cut off mechanism of the low pressure cylinder, and a gage having two pointers connected respectively to the said two arms, for indicating the range of cut off in the cylinders.

ERNEST LEWIS.
